UNITED STATES PATENT OFFICE.

CHARLES A. CADWELL, OF CLEVELAND, OHIO, ASSIGNOR TO THE ELECTRIC RAILWAY IMPROVEMENT COMPANY, OF CLEVELAND, OHIO, A CORPORATION OF OHIO.

ELECTRIC FURNACE.

Application filed April 29, 1920. Serial No. 877,430.

The present improvements relating, as indicated, to an electric furnace, have more particular regard to a furnace of this type adapted for operating with an electric current of relatively high voltage, such for example, as is ordinarily used in municipal lighting and heating circuits and for the operation of electrical railways. In general, my improved furnace is of the type wherein a resistor of granular material is employed in conjunction with a plurality of electrodes so disposed relatively to such resistor that arcs are formed from one electrode to said resistor and from the latter to the other electrode. This type of furnace is adapted for use as a crucible furnace by enclosing the parts in question in a suitable chamber adapted to permit a crucible to be placed between the two electrodes, such crucible preferably resting on the intermediate resistor. However, by suitable modifications, such furnace may also be adapted for use as a muffle or re-heating furnace.

The object of the present invention is to so construct and arrange the resistor element in a furnace of this type as to secure maximum efficiency from the passage of the current therethrough, while at the same time retaining the heating effect of the arcs produced between said resistor and the respective electrodes. A further object of the invention is to provide means for readily adjusting the position of the electrodes relatively to the resistor, as well as for raising and lowering such electrodes incidentally to starting and stopping operation of the furnace. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, several of the various mechanical forms in which the principle of the invention may be carried out.

In said annexed drawings:—

Fig. 1 is a plan view of a furnace embodying my present improvements, such furnace being primarily designed for heating crucibles; Fig. 2 is partly a side elevation and partly a vertical central section of such furnace, the plane of the section being in-

dicated by the line 2—2, Fig. 1; Fig. 3 is a broken plan view of the interior of said furnace as illustrated in Figs. 1 and 2; Fig. 4 is a view similar to Fig. 3, but showing a modification in construction of the resistor; Fig. 5 is a broken vertical section showing still another modification in the construction of such resistor; Fig. 6 is partly a plan view and partly a horizontal section, and Fig. 6a is a sectional detail of another furnace embodying the present improvements, said furnace being more particularly designed as a muffle or re-heating furnace; Fig. 7 is a horizontal section of still another form of furnace embodying my present improvements, such furnace likewise being adapted for use as a re-heating or muffle furnace; and Fig. 8 is a central vertical section of such last mentioned form of furnace, the plane of the section being indicated by the line 8—8, Fig. 7.

Referring first of all to the construction of furnace shown in Figs. 1, 2 and 3, such furnace will be seen to comprise an outer casing 1, preferably of sheet metal and of any desired shape and size, although a convenient shape where the furnace is to be used to heat crucibles is the elliptical one shown. The sides and bottom of this casing are interiorly lined first with a layer 2 of suitable heat non-conducting material such as infusorial earth; then with a second thicker layer 3 of silica. The bottom of the furnace chamber thus provided is furthermore preferably covered with a layer 4 of magnesia or equivalent material, it being upon this that the resistor 5 is in turn placed. To facilitate the draining of spilled metal or other material from the interior of the furnace chamber, the several layers composing the bottom thereof are pierced by a hole 6 which is normally closed with a plug 7 of silica sand held in place by means of a suitable retaining plate 8 (see Fig. 2). Resting on the side walls of the chamber, but preferably contained within the upper edge of casing 1, is a suitable cover preferably consisting of two spaced blocks or heavy plates 10, 10 of heat-resistant material, the space between such blocks being filled in by means of a third block or plate 11 resting thereon and removable when desired in order to afford access to the interior of the chamber so as to permit of the insertion or removal of crucibles 12 or the like.

Each of said blocks 10 is formed with an aperture 13 through which a carbon electrode 14 is inserted so as to project downwardly with its lower end in contact or close proximity, as desired, with the resistor 5. The construction of the mountings or holders for such electrodes, is clearly shown in Fig. 1, from which it will be seen that the electrode proper, which will ordinarily consist of a cylindrical carbon pencil, has its upper end closely fitted in a metal tube 15 provided with a flanged cap 16 of insulating material. This tube 15 is held in vertically adjusted position in an outer tubular member 17 by means of a set screw 18, whereby the position of the electrode may be from time to time changed with respect to said member, as will be readily understood. The body of said member 17 is spaced from the tube 15 in which the electrode is directly held and is both rotatably and axially adjustable within a tubular housing 19 that is supported on block 10 by means of bracket arms 20. The latter do not come in contact with the metal casing 1, and said housing, it will thus be seen, is effectually electrically insulated from the remainder of the furnace structure, the current leads 21 being suitably connected as shown in Fig. 2 to said housings, respectively.

Member 17 is provided with a flange 22 that in the normal position of parts rests on the upper end of the housing and so determines the normal or operative position of the electrode carried by said member, any adjustment of said normal position being accomplished by loosening set screw 18 and correspondingly raising or lowering tube 15 in which said electrode is held. For the purpose, however, of quickly raising the electrode from such operative position or for restoring the same thereto, a series of steep helical slots 25, three in number, as shown, is cut in the housing 19 and pins 26, one of which is provided with a handle 27, projecting radially from member 17 into said slots so that upon rotation of said member the desired raising or lowering of the same, and thus of the electrode, is expeditiously accomplished.

The resistor 5 is principally made up of a substantial layer of material, preferably granular carbon or some similar conducting material, of relatively high resistance. The current, accordingly, in passing lengthwise through the bed of material composing the resistor generates heat, due to the resistance encountered and thus supplements the heating effect of the arcs between the respective electrodes 14 and such resistor. As a matter of fact, blocks 30 of solid carbon or graphite are placed on top of the bed of granular material, thus composing the resistor, directly beneath said electrodes, and it is between the latter and such blocks that the arcs

will be formed, such blocks being preferably opposed to the electrodes in order more exactly to define or limit the lowermost positions of the latter.

With a resistor of the character described, I have found that the heat generated by the passage of the electric current is greatest along the bottom of the furnace chamber, which is objectionable, not only because it tends to burn out such bottom, even where composed of magnesite or equivalent highly refractory material, but also because there is a corresponding loss in efficiency. In other words, it is obviously desirable that the greatest heat should be developed as near the top surface of the resistor as possible in order to more efficiently heat the crucible 12 or other object located in the furnace chamber. The tendency of the current thus to flow along the bottom of the resistor is, of course, due to the fact that the radiation of heat is least from this portion of said resistor and the higher the temperature of the material composing said resistor, the lower the electrical resistance. This tendency is also in part to be attributed to the greater density of the granular material in the lower stratum of the bed, which induces a slightly greater initial current flow through such lower stratum in preference to the upper stratum of the bed. As a result, the temperature begins at once to rise in such lower stratum more rapidly than in the upper, and as the temperature rises, the electrical conductivity of the channel or channels which the current makes for itself increases until nearly all such current follows the resulting incandescent streak and the material that forms the adjacent nonconducting surface is subjected to a destructive temperature along such incandescent streak.

To overcome the foregoing difficulty, accordingly, I have found that it is necessary to so construct or form the resistor 5 as to force and maintain the current flow through the upper portion or stratum of said resistor rather than along its lower surface. To accomplish this result, briefly stated, I make said resistor of horizontal layers of different conductivity, so that the current density will be greatest in a plane raised a suitable distance above the floor, preferably approximately midway between the bottom and top surfaces of the resistor. Thus, where the bed of granular material composing the resistor is an inch deep, the greatest current density should be in a plane approximately one-half inch above such floor; then the upper portion of the resistor will become at least equally as highly heated as the lower portion and will radiate heat into the space, wherein the article to be heated is located, in an efficient manner.

I have devised various means for accomplishing the foregoing result. Thus, as shown

in Figs. 2 and 3, I simply imbed in the body of granular material composing the resistor as aforesaid, a plurality of cylindrical carbon pencils 31, such pencils being disposed transversely of the longitudinal axis of the furnace, or, in other words, transversely of a line passing through the electrodes 14. The pencils preferably lie clear of the magnesite floor 4 and are, to an equal extent, covered above by said granular material. As a result, the plane in which the horizontal diameters of said pencils lie, will present a path of least resistance to the flow of current from the one electrode to the other through the resistor, so that both initially and after the furnace becomes heated, this plane will have the greatest current density. By varying the diameter of the pencils or rods 31, as also by varying their number and spacing, the total resistance of the resistor to such current flow, and thus the voltage required, may be varied to suit different conditions of use and current supply. At the same time, where, as illustrated in the figures in question, the furnace is used to heat crucibles, a suitable number of pencils or rods 31 may be located directly beneath the surface of the resistor on which the crucible or crucibles are intended to rest, thus assuring a proper support for the latter and preventing their sinking into the granular material, which obviously will interfere with successful operation of the furnace.

In place of such cylindrical rods I may utilize approximately spherical balls 32 either arranged in transverse rows as shown in Fig. 4, or otherwise distributed in the bed of granular material constituting the resistor. The result will obviously be as before the creation of a plane of lower resistance above the floor for the passage of the current through the resistor. In Fig. 5, I show in place of the cylindrical rods, a series of transverse bars 33 of irregular polygonal form in cross section, such bars having their maximum diameters disposed in a plane above the upper surface of the bed 4 as in the case of the two previously described structural forms of resistor.

Where it is desired to employ the furnace as a muffle furnace or for re-heating articles, a chamber 35 extending longitudinally of the furnace chamber proper, as shown in Fig. 6, may be utilized. This chamber is preferably of circular cross section and may consist of an alundum tube, the respective ends of which are adapted to be closed by removable plugs 36 of the same material as the wall 3 of the furnace chamber. Transversely disposed in the space on either side of said tube 35 is a series of short carbon rods 37, preferably cylindrical in cross section just as the rods 31 in the first described structural form of my furnace. The outer ends of these rods may be conveniently imbedded in the adjacent side walls of the furnace chamber, while their inner ends are curved to conform with the cylindrical sides of said tube or heating chamber 35 (see Fig. 6a). These rods, as well as such tubular chamber, are then imbedded in a mass of granular material the same as composes the main portion of resistor 5 in such previously described construction, and electrodes preferably in the form of plates 38 are mounted within the furnace chamber in the same general relation to the granular bed as before, except that such plates enter into such bed, so that arcs between same and bed are smothered. As a result, upon the passage of current through the electrodes and the composite resistor thus provided, the heating effect of the current passing through the granular material serves to bring the chamber 35 to the proper degree of temperature. Just as in the case of rods 31, so the rods 37 provide a path of least resistance for the current through the resistor alongside the heating chamber 35 in a plane above the floor of the furnace chamber.

Instead of a longitudinally disposed heating chamber such as just described, one or more transversely extending chambers 40 may be utilized, as shown in Figs. 7 and 8. Said chambers 40, however, are themselves formed of hollow carbon blocks, preferably of the cylindrical shape illustrated, and of such size as to provide an adequate interior space for the reception of the article to be heated. These tubular carbon chambers are lined with a layer 41 of alundum or similar plaster, and their open ends are adapted to be closed by means of removable plugs 42 similar to the plug 36. Said chambers 40 are then imbedded in a mass of granular material 42 and carbon electrodes 43, here shown as extending down into such material, provide the means for passing the current through the latter. Just as in the case of the rods 31 and 37 in previously described constructions, so here, the hollow carbon members 40, which at the same time constitute the heating chambers, obviously serve to decrease the electrical resistance for the passage of such current in a plane spaced above the floor of the furnace chamber. In other words, the path of greatest current density will include such chambers instead of being deflected along the floor of the furnace, where it would be relatively ineffective.

Other modes of applying the principles of my invention may be employed instead of the one explained, change being made as regards the mechanism herein disclosed, provided the means stated by any of the following claims or the equivalent of such stated means be employed.

I therefore particularly point out and distinctly claim as my invention:

1. In an electric furnace, the combination

of a suitable chamber providing an exteriorly accessible space for the reception of the work to be heated; electrodes extending into said chamber; and a resistor exposed within said chamber and lying between said electrodes, said resistor being constructed so as to provide paths of varying resistance for the current in passing from one of said electrodes to the other.

10. 2. In an electric furnace, the combination of a suitable chamber providing an exteriorly accessible space for the reception of the work to be heated; electrodes extending into said chamber; and a resistor exposed within said chamber and lying on the floor thereof between said electrodes, said resistor being constructed so as to provide a path of least resistance for the current in passing from one of said electrodes to the other in a plane spaced from such floor.

3. In an electric furnace, the combination of a suitable chamber providing an exteriorly accessible space for the reception of the work to be heated; electrodes extending into said chamber; and a resistor exposed within said chamber and lying on the floor thereof between said electrodes, said resistor consisting of granular carbon and members of greater relative electrical conductivity imbedded therein.

4. In an electric furnace, the combination of a suitable chamber providing an exteriorly accessible space for the reception of the work to be heated; electrodes extending into said chamber; and a resistor exposed within said chamber and lying on the floor thereof between said electrodes, said resistor consisting of granular carbon and solid members of similar material imbedded therein.

40. 5. In an electric furnace, the combination of a suitable chamber providing an exteriorly accessible space for the reception of the work to be heated; electrodes extending into said chamber; and a resistor exposed within said chamber and lying on the floor thereof between said electrodes, said resistor consisting of granular carbon and solid members of similar material imbedded therein, and having their maximum horizontal dimensions disposed in a plane spaced from such floor.

55. 6. In an electric furnace, the combination of a suitable chamber providing an exteriorly accessible space for the reception of the work to be heated; electrodes extending into said chamber; and a resistor exposed within said chamber and lying on the floor thereof between said electrodes, said resistor consisting of granular carbon and a plurality of elongate solid members of similar material arranged transversely of the path of the current through said resistor and having their maximum diameters disposed in a plane spaced from such floor.

60. 7. In an electric furnace, the combination

of a suitable chamber providing an exteriorly accessible space for the reception of the work to be heated; electrodes extending into said chamber; and a resistor exposed within said chamber and lying on the floor thereof between said electrodes, said resistor consisting of granular carbon, and a plurality of carbon rods arranged transversely of the path of the current through said resistor.

8. A heating unit for an electric furnace of the type described, comprising a resistor composed of granular carbon and solid members of similar material imbedded therein in non-contacting relation and having their maximum horizontal dimensions located in a plane intermediate the top and bottom surfaces of said resistor.

9. A heating unit for an electric furnace of the type described, comprising a resistor composed of granular carbon and a plurality of elongate solid members of similar material arranged in non-contacting relation transversely of the path of the current through said resistor and having their maximum diameters located in a plane intermediate the top and bottom surfaces of said resistor.

10. In an electric furnace, the combination of a suitable chamber providing an exteriorly accessible space for the reception of the work to be heated; electrodes extending into said chamber; a resistor exposed within said chamber and lying between said electrodes, said resistor being composed of granular carbon; and blocks of solid carbon located on said resistor adjacent the ends of said electrodes.

11. In an electric furnace, the combination of a suitable chamber; electrodes extending therein; a resistor within said chamber lying between said electrodes, means for adjusting the normal position of said electrodes relatively to said resistor; and other means adapted to move said electrodes from and restore same to such normal position.

12. In an electric furnace, the combination of a suitable chamber; electrodes extending therein; a resistor within said chamber lying between said electrodes; and means for adjusting the position of said electrodes relatively to said resistor, said means each including a stationary housing, a member vertically movable therein; and clamp means adjustably securing the electrode to said member.

13. In an electric furnace, the combination of a suitable chamber; electrodes extending therein; a resistor within said chamber lying between said electrodes; and means for adjusting the position of said electrodes relatively to said resistor, said means each including a stationary housing, a member having screw-thread connection with said housing whereby it may upon rotation be ver-

tically moved therein, and clamp means adjustably securing the electrode to said member.

14. In an electric furnace, the combination of a suitable chamber; electrodes extending therein; a resistor between said electrodes; members of greater relative electrical conductivity embedded in said resistor; and a chamber embedded in said resistor and adapted to receive articles to be heated, said chamber being of greater electrical conductivity than the resistor.

15. In an electric furnace, the combination of a suitable chamber; electrodes extending therein, a resistor between said electrodes; members of greater relative electrical conductivity embedded in said resistor; and a chamber embedded in said resistor transversely to a line between said electrodes and adapted to receive articles to be heated, said chamber being of greater electrical conductivity than the resistor.

Signed by me this 24 day of April, 1920.
CHARLES A. CADWELL.
